RESILIENT PAD FOR WRIST WATCHES

Frank C. Pachter, Chicago, Ill.

Application May 13, 1949, Serial No. 93,121

1 Claim. (Cl. 224—4)

1

The invention relates to resilient pads for wrist watches and has reference in particular to pads of leather or similar decorative material which will enhance the appearance of the watch in addition to providing the desired resiliency and protection for the wrist.

A general object of the invention is to provide a pad of resilient material as a backing for a wrist watch and which pad will lie flat against the wrist of the wearer and in so doing will hold the pad in assembled relation on the watch.

A more specific object of the invention is to provide a resilient backing pad for a wrist watch which will have cuts or slots therein arranged longitudinally and transversely whereby to permit convenient attachment of the pad to and release from the strap or band of the watch.

Another object is to provide a resilient and non-slip backing for a wrist watch which may consist of a pad of leather or other material and which will be held in place with respect to the watch by means of the strap or band holding the watch to the wrist.

With these and various other objects in view, the invention may consist of certain novel features of construction and operation, as will be more fully described and particularly pointed out in the specification, drawings and claim appended hereto.

In the drawing which illustrates an embodiment of the device and wherein like reference characters are used to designate like parts—

Figure 1 is a top plan view of a man's wrist watch having a strap to which is affixed the resilient pad of the invention;

Figure 2 is a plan view showing the underside of the pad and illustrating the longitudinal and transverse slots by means of which the pad is releasably affixed to the watch; and

Figures 3 and 4 are views in plan showing resilient pads of different shape for various types of wrist watches, said pads, however, having the same basic arrangement of longitudinal and transverse slots.

Referring to the drawings, and particularly Figure 1, a wrist watch is disclosed identified generally by numeral 10, the same having the usual face 12, hands 13 and 14, and winding stem 15. Such watches are conventional and it is customary to affix the watch to the wrist by means of a strap 16 with one section of the strap having secured to the watch end 17, the other section of the strap being secured to the watch in a similar manner at end 18.

The invention provides a resilient pad for

2

wrist watches and the watch 10 has been selected to illustrate the manner of releasably affixing the pad to the strap so that the pad will underlie and provide a backing for the watch. The pad indicated by numeral 20 may consist of leather, imitation leather, synthetic plastics of the type having rubber-like characteristics, processed cloth, rubber or similar materials having a certain amount of resiliency, adequate strength and non-skid properties. In order that the pad may be quickly assembled with the watch the same is provided with a central longitudinal slot or cut 21 extending almost the entire length of the pad on the longitudinal center line thereof, terminating short of each end, however, to provide arcuate end portions 22. The transverse slots or cuts 23 and 24 at the respective ends of the pad are arcuate in order to substantially parallel the terminal edges of the pad. These transverse cuts join with the center longitudinal cut 21 with the result that two flaps 25 and 26 are formed.

In assembling such a resilient pad with the wrist watch 10, as shown in Figures 1 and 2, the pad is placed against the back of the wrist watch with the watch in contact with the top or decorative surface of the pad. This will locate the underside or non-skid surface of the pad against the wrist of the wearer. The ends of strap 16 are then inserted through the transverse slots 24, this operation being facilitated by the central longitudinal slot since the flaps 25 and 26 can be bent out of the plane of the pad for locating the strap. When the flaps are released they return to a substantially flat position against the back of the watch and with the pad in contact with the wrist of the wearer it will be understood that the same lies substantially flat and in so doing effectively interlocks itself to the watch or at least to the strap or band extending from the respective ends of the watch.

In the place of the strap 16 it is customary with some manufacturers to employ metal or fabric bands which, however, are fixed to the watch in substantially the same manner as straps. The resilient pad of the invention can be combined with metal or fabric bands by means of the transverse cuts 23 and 24 in the same manner as described with respect to the strap and as clearly illustrated in Figures 1 and 2. In such cases it is absolutely essential that the longitudinal center cut extend from one transverse slot to the other. If this cut is not provided it is impossible to interfit the pad with the band at the respective ends of the watch. However, as regards a strap,

the two ends can be readily inserted in the transverse slots so that the longitudinal cut forming flaps 25 and 26 are not essential.

The resilient pad shown in Figures 1, 2 and 3 is substantially oblong in shape so as to approximately coincide with the general contour of the watch although the pad will be somewhat larger in size to provide the marginal edge including the end portions 22. Of course, the pad of the invention is not restricted to any particular shape and any shape that may be employed such as will best suit the watch with which the pad is to be used. For example, in Figure 4, the resilient pad 30 has straight ends providing straight end portions 32. In this modification the sides have a curvature which in some cases may be desirable since the marginal edge thus provided will fully protect the wrist of the wearer against contact with the watch. However, in this design the same basic arrangement of cuts is employed including the center longitudinal cut 31 and the transverse end cuts 33 and 34 whereby flaps 35 and 36 are formed. The pad of the invention will enhance the appearance of the watch in addition to providing resiliency and a non-skid backing therefor. It is relatively easy to affix the pad although the pad is positively prevented from working loose by the manner in which the end portions are caused to overlie the strap or band of the watch.

The invention is not to be limited to or by details of construction of the particular embodiment thereof illustrated by the drawings as various other forms of the device will of course be apparent to those skilled in the art without departing from the spirit of the invention or the scope of the claim.

What is claimed is:

In an article of the character described, a pad of flexible material adapted to form a backing for a wrist watch by being releasably affixed to the endless band or strap of the watch, said pad having a transverse cut at longitudinally opposite ends respectively and through which the band or strap is adapted to extend, said pad having a longitudinally extending center cut connecting the transverse cuts to form a pair of flaps, said flaps being bendable when the endless band or strap is passed through the opening provided by the longitudinal cut in affixing the pad to the band or strap, and each transverse cut forming an end portion which overlies the band or strap when in affixed relation thereon, with the flaps lying substantially flat and forming a backing for the watch.
